BLADE MOUNTING FOR PROPELLERS

Columbus R. Sacchini, Willoughby, Ohio, assignor to The Marquette Metal Products Company, Cleveland, Ohio, a corporation of Ohio

Application December 21, 1945, Serial No. 636,363

9 Claims. (Cl. 170—160.3)

1

This invention relates to controllable pitch propellers and particularly to the mounting of the propeller blade thereof in a hub, and is an improvement on the propeller blade mounting disclosed in the copending application of Gordon W. Hardy, Serial No. 528,412, filed March 28, 1944.

One of the principal objects of the present invention is to provide, in a controllable pitch propeller, a blade mounting by which the blades can be installed, initially adjusted, and removed for servicing of themselves and of their control mechanism, more easily and in less time than heretofore required, and by virtue of which the pitch of the blades can be adjusted after assembly in the hub.

Another object is to provide a combined blade retaining sleeve and blade adjusting gear for mounting the blade in the hub and for connecting it to the pitch control mechanism, and which is simple in construction, easily installed, maintains the blade shank in proper position axially while permitting proper rotation thereof about its axis for adjustment, permits initial positioning and securing of the blade and blade gear accurately in relatively rotated positions of adjustment with respect to each other, after installation, and maintains the blade and gear accurately in all controlled positions of the blade.

A more specific object is to provide a pair of complementary hemi-cylindrical sleeve sections which cooperate to form a cylindrical retaining sleeve for a propeller blade shank and one of which has a blade driving gear integral therewith and positioned to be coaxial with the assembled sections and to cooperate accurately with the main driving gear of the propeller hub when the blade is installed.

Other objects and advantages will become apparent from the following description wherein reference is made to the drawings in which:

Fig. 1 is a side elevation of a hub and blade assembly embodying the blade mounting of the present invention, part thereof being shown in section for clearness in illustration;

Fig. 2 is a top plan view of one of the blade mountings illustrated in Fig. 1;

Fig. 3 is a front elevation of the blade mounting illustrated in Fig. 2, part thereof being shown in section for clearness in illustration; and

Fig. 4 is a cross sectional view of the blade supporting barrel of the hub with a blade mounted therein, and is taken on the line 4—4 of Fig. 1, the roller bearings being shown in elevation for clearness in illustration.

As more fully set forth in the copending ap-

2

plication above identified, considerable difficulty has been encountered in providing an easily installed blade mounting which permits adjustment of the blade for pitch after installation of the blade in the hub and which supports the blade shank in proper relation to the blade gear and the latter in proper relation to the main driving gear. One mounting for this purpose is illustrated in the above identified copending application and, in the form there shown, while the mounting assembly is relatively simple and easily constructed, its installation and removal for purposes of servicing of the parts thereof or of the operating mechanism within the hub is difficult and time consuming. Furthermore, the pitch of the blade associated therewith cannot be adjusted after installation of the blade and retainer subassembly in the hub.

In accordance with the present invention, a simplified and more easily installed mounting for a propeller is provided and is arranged to co-operate with the control mechanism such as fully disclosed in said copending application.

As therein more fully described, the propeller 25 comprises generally an annular hub 1 which is generally in the form of a central segment of a sphere with inturned radial flanges at its ends and which has a plurality of blade supporting barrels or arms 2 spaced apart from each other 30 about its periphery and preferably integrally secured thereto or formed integral therewith. In the form illustrated herein, two such barrels are provided, although three or four barrels angularly spaced equidistantly about the axis of the hub may be provided.

The hub 1 is mounted on, and in coaxial relation with, a hub carrier 3 which has a peripheral flange 4 near its rear end and an annular shoulder 5 near the periphery of the flange for receiving the inner edge of one of the end flanges of the hub 1 so as to center the hub in proper coaxial relation to the carrier 3. The hub is secured rigidly in position on the shoulder 5 by means of a plurality of circumferentially spaced bolts 6.

The carrier 3 has a tapered internal bore 7 in which is fitted the crank shaft 8 of an engine (not shown), a suitable key 9 being provided for interlocking the carrier 3 and shaft 8 against rotation relative to each other. The shaft 8 extends axially entirely through the carrier 3 from the rear end of the carrier and beyond its forward end and is threaded, as indicated at 10, adjacent to the forward end of the carrier 3. A tubular nut 12 having an internally threaded in-

ner end portion 13, is in threaded engagement with the threaded portion 10 of the shaft 8 for holding the carrier 3 in fixed axial position on the shaft 8.

Mounted in surrounding and coaxial relation to, and rotatable relative to, the nut 12 is a gear hub or sleeve 14 on one end of which is a bevel gear 15 which is the master power gear for operating the blades of the propeller to vary or control their pitch. The sleeve 14 is also provided with an external spur gear 16 positioned forwardly from the bevel gear 15. The gear 16, in turn, is drivingly connected to a plurality of racks 17 which are preferably formed on and integral with pistons 18 of suitable servomotors, the cylinders of which are indicated at 19. As illustrated, the cylinders 19 are so positioned that the pistons 18 and racks 17 can reciprocate tangentially of the pitch diameter of the gear 16 as to oscillate the master gear 15 about the axis of the shaft 8.

The servomotors are carried in a suitable housing 20 which has a peripheral flange 21 on which is an annular shoulder 22. The shoulder 22 engages the inner edge of the forward flange of the hub 1 and centers the housing 20 in coaxial relation with respect thereto. The servomotor housing 20 is secured to the hub 1 by means of a circumferential series of bolts 23 and, in addition to being the housing for the servomotor, provides an external radial thrust bearing and an adjacent axial thrust bearing for the sleeve 14, as indicated at 24.

Operating fluid is supplied to the servomotors as fully set forth in the above identified copending application. The discharge of fluid from the motors is into a sump 25 which is defined by the annular flange 4 of the carrier 3 and a suitable cover plate 26, and, in turn, is connected in the hydraulic system, all as fully set forth in the above identified copending application.

The propeller blades are mounted in the blade supporting barrels or arms 2 and must be mounted therein in coaxial relation thereto and for correlated rotation or oscillation about their respective axes. At the same time adequate thrust to resist the centrifugal force of the blades must be provided in a manner such that the blades do not bind and resist rotation about their axes to different controlled positions. Likewise the blades must be interlocked with each other through the control mechanism so that once they are set in the properly adjusted position initially with respect to each other, subsequent rotation of one blade for varying its pitch is impossible without a complementary and equal rotation of the other. They must be arranged so as to permit the proper initial setting of each blade with respect to the control means itself so that thereafter they are operated in the proper balance and relation by the control means. They should be mounted so that they can be installed and removed easily and quickly and initially adjusted for pitch after installation in the hub. Finally, since the blades are made of aluminum or relatively soft metal, they must be provided with large anchorage corrugations to resist centrifugal force.

In order to accomplish all of these results in a simple and rugged structure, the mounting of the present invention is provided. In the illustrative embodiment, the mounting is shown as adapted for use with the usual blades 27, each of which has an integral shank portion 28 provided with external annular corrugations 29 and a pilot

surface 30, the latter being at the innermost end of the shank. Since each blade is mounted in the same manner, the mounting of one blade only is described in detail herein.

As best illustrated in Figs. 1, 2 and 3, a blade shank retainer or mounting, indicated generally at 31, is provided. The retainer 31 is in the form of a split sleeve and comprises a pair of complementary hemi-cylindrical shank retaining sleeve sections, designated at 32 and 33, respectively, which are arranged to fit together in firmly embracing relation to the shank 28 of the blade and are provided with internal annular corrugations, indicated generally at 34, which are complementary to and fit the corrugations 29 of the shank. The hemi-cylindrical sleeve section 32 is provided at one end with an integral hub extension 35 which is coaxial with the assembled sleeve sections and which carries, near its innermost end, a bevel gear 36 which constitutes the blade gear for oscillating the blade associated with the retainer 31. The retainer 31 is provided between its ends with an external annular shoulder 37 and the extension 35 is provided with an axial bore 38, the innermost end of which is in the form of an internal annular bearing surface 39. The carrier 3 is provided with radially extending cylindrical bosses 40 on which are mounted suitable bushings or external annular bearings 41 which engage and are complementary to the bearing surface 39 of the extension 35 and provide the pilot and radial thrust bearing for the retainer or mounting 31 when the retainer 31 is installed in the barrel 2 with the gear 36 in proper mesh with the main driving gear 15.

At its opposite end, the retainer 31 has a cylindrical clamping portion 42 which is adapted to embrace the shank 28 of the blade outwardly axially beyond the barrel 2. The portion 42 has slots 43 which extend from its outer end longitudinally of the portion 42 for a sufficient distance to provide flexibility of the portion 42. The portion 42 has an external annular groove 44 which lies in the slotted portion and accommodates a clamping band 45 which, by means of a suitable bolt 46, and its cooperating nut, is operated to draw the portion 42 into firm clamping engagement with the shank 28 when the blade is in the desired relatively rotated initial adjusted position with respect to the retainer 31 and secures the blade shank 28 and the sections 32 and 33 for rotation together. The hemi-cylindrical sections 32 and 33 are also held in embracing relation to the hub 28 of the blade by means of an endless annular band 47 which is fitted onto the assembled sections after the blade shank has been embraced therein, preferably with a slip fit to facilitate disassembly. The band 47 may be a bronze bearing or, as illustrated, may be a hard metal race suitable for thrust roller bearings 48, the inner wall of the barrel 2 forming the outer race of the bearings 48. The bearings 48 are preferably of such length as to fit freely between the inward face of the flange 37 of the retainer 31 and an outwardly facing shoulder 49 of the blade supporting barrel.

At the outermost face of the flange 37, a suitable combined axial and radial thrust bearing is provided. In the form illustrated, a suitable bearing race 50 is slip fitted onto the assembled sleeve sections 32 and 33 and firmly against the outward face of the flange 37. A complementary race 51 is screw threaded into the open end of the barrel 2 so as to retain the ball bearings 52,

and through them, the retainer 31, in proper axial and radial position in the barrel 2. The outermost end of the barrel 2 has a plurality of notches 53 and the outer end of the race 51 has a plurality of notches 54, so that, when the race is in proper position in the barrel, a suitable key 55 may be inserted in aligned notches of the barrel and outer race for anchoring the race 52 against rotation. The key 55 may be secured in place by suitable screws, not shown, extending through the key 54 and in threaded engagement with the end of the barrel 2.

As more fully described in the above identified copending application, a different number of notches 53 is provided in the outer end of the barrel and in the race 52 so as to provide a vernier effect between the notches of one and the other to permit closer setting of the race 52, while providing for insertion of the key 55 in the adjusted position. As disclosed in the above copending application, the practice has been to make the retaining sleeve in two sections, the two sections being threaded at their inner end so as to receive, in threaded engagement, the outer end of a shank of a blade gear comparable to the gear 36. This gear shank is hollow and receives axially a retaining bolt which is in threaded engagement with an axial bore in the inner end of the shank of the installed propeller blade. A sleeve that is split longitudinally after threading is difficult to assemble into or on to a complementarily threaded part. Moreover, because of the larger number of parts required and precise relationship between them, the construction according to said copending application is much more expensive than the present one.

With the present structure the blade can be readily installed in the retainer or mounting 31 and the assembled blade and mounting installed readily in the barrel 2 of the hub.

In order to install a blade, the servo-motors are operated to set them and the master gear 15 at low pitch position of the blades. The retaining sleeve sections 32 and 33 then are placed in embracing relation to the blade shank and the bearing or race 47 and the race 50 are then installed by slip fitting them into place on the sleeve sections. The clamping band 45 is installed and holds the blade approximately at the pitch desired. This subassembly is then inserted into its associated barrel with the roller bearings 48 in place thereon and while held in a rotated position to mesh the segmental blade gear 36 at its circumferential midpoint with the master gear 15. The axial thrust bearing 52 and the race 51 are then installed, adjusted for balance of the blades about the hub axis and secured in adjusted position by the key 55.

The clamping band 45 is then loosened and, with the servo-motor remaining at low pitch and the segmental gear centered and meshed with the master gear 15, the blade is rotated in the sleeve sections 32 and 33 about its axis to low pitch position, the final position being determined accurately with a protractor. Thereupon the clamping band 45 is again tightened. Thus the blade can be adjusted after assembly in the barrel 2. Since the pitch of the blades is seldom varied more than a few degrees, the blade gear 36 may be segmental, as illustrated. If desired, the blade gear, with only a slight addition in weight, can be a complete gear, in which case any of its teeth can be engaged initially with the master gear when the blade and retainer sub-assembly is inserted in the barrel, and the blade

then rotated in the sleeve sections to the adjusted position. The use of a complete gear 36 is advantageous for purposes of assembly.

Once this installation of the blades is made, 5 all of them maintain a fixed degree of pitch relative to each other as the gears 15 and 36 are extremely accurate and free from backlash.

The assembly and disassembly of the other parts of the hub are fully disclosed in said copending 10 application. If the complementary tapered surfaces of the hub carrier and shaft 8 are lubricated before mounting of the hub carrier on the shaft, then by rotating the nut 12, as by a wrench engaging a cross hole in the nut, the entire propeller hub can be moved endwise in the direction of taper of the shaft 8 and thus loosened for removal as a unit. This is due to engagement of the nut 12 with the inner radial wall of the gear hub 14 and engagement of the hub 14 with the 15 thrust bearing surface on the inner wall 21 of the servo-motor housing 20. Again, the servo-motor housing and the servo-motors carried thereby can be removed as a unit for service and repair by removing the bolts 23, and the gears 15 and 16 20 can be removed readily after removal of the housing 25 20.

I claim:

1. In a variable pitch propeller, a hub, a blade supporting barrel extending radially of the hub, a propeller blade, a blade shank thereon and having external annular corrugations, a pair of complementary hemi-cylindrical shank retaining sleeve sections embracing the shank and having internal corrugations fitting the corrugations of the shank, means for securing the hemi-cylindrical sleeve sections in embracing relation to and in coaxial relation with the blade shank, means supporting the assembled retaining sleeve sections in fixed axial position in the barrel and 40 for rotation about their common axis, means securing the blade shank and retaining sleeve sections for rotation together about said common axis, one of said hemi-cylindrical sleeve sections having at its inner end an integral extension 45 offset from the associated sleeve section, coaxial with the shank and projecting into the hub, a blade gear on and rigid with and coaxial with the extension, and driving means in the hub 50 drivingly connected to said gear for varying the pitch of said blade.

2. In a variable pitch propeller, a hub, a plurality of blade supporting barrels extending radially of the hub, the axes of said barrels lying in the same plane and intersecting and spaced uniformly circumferentially of the hub, at a common point in the hub, blades respective to the barrels, a blade shank on each blade and having external annular corrugations, a plurality of pairs of complementary hemi-cylindrical shank retaining sleeve sections, each pair embracing a shank, means for securing each pair of the hemi-cylindrical sleeve sections in embracing relation about and in coaxial relation with its associated shank, means supporting each pair of the assembled retaining sleeve sections in fixed axial position in its associated barrel and for rotation about the common axis of its sections, means securing each blade and its associated retaining sleeve sections for rotation together about their common axis, 65 one hemi-cylindrical sleeve section of each pair having an integral extension at its inner end offset therefrom into coaxial relation to the shank and projecting into the hub, blade gears on and rigid with the extensions, respectively, a drive shaft coaxial with the hub and having its

axis, intersecting said point, a master driving gear in the hub coaxial with the shaft and engaged with all of said blade gears for driving said gears and adjusting the blades concurrently, and means in the hub drivingly connected to the main driving gear for driving the same.

3. In a variable pitch propeller, a hub, a blade supporting barrel extending radially of the hub, a propeller blade, a blade shank thereon and having external annular corrugations, a pair of complementary hemi-cylindrical shank retaining sleeve sections embracing the shank and having internal corrugations fitting the corrugations of the shank, means for securing the hemi-cylindrical sleeve sections in embracing and coaxial relation with the shank, means supporting the assembled retaining sleeve sections in fixed axial position in the barrel and for rotation about their common axis, one of said hemi-cylindrical sleeve sections having an integral extension at its inner end offset therefrom into coaxial relation to the shank and projecting into the hub, a gear rigid and coaxial with the extension, driving means in the hub drivingly connected to said gear for varying the pitch of said blade, and clamping means on the outer end of said sleeve sections and accessible while the assembled sleeve sections and blade shank are mounted in the barrel, for clamping the sleeve sections into firm engagement with the shank for rotation therewith.

4. In a variable pitch propeller, a hub, a blade supporting barrel extending radially of the hub, a blade, a blade shank thereon and having external annular corrugations, a pair of complementary hemi-cylindrical shank retaining sleeve sections embracing the shank and having internal corrugations fitting the corrugations of the shank, means for securing the hemi-cylindrical sleeve sections in assembled relation about and in coaxial relation with the shank, means supporting the assembled retaining sleeve sections in fixed axial position in the barrel and for rotation about their common axis, means securing the blade and retaining sleeve sections for rotation together about said common axis, one of said hemi-cylindrical sleeve sections having an integral extension at its inner end coaxial with the shank and projecting into the hub, a gear integral and coaxial with the extension, driving means in the hub drivingly connected to said gear for varying the pitch of said blade, said extension being open at its inner end and having an annular internal bearing surface coaxial with the extension, and bearing means within and rigid with the hub and coaxial with and fitting the bearing surface of the hemi-cylindrical sleeve.

5. In a variable pitch propeller, a hub, a blade supporting barrel extending radially of the hub, a blade, a blade shank thereon and having external annular corrugations, a pair of complementary hemi-cylindrical shank retaining sleeve sections embracing the shank and having internal corrugations fitting the corrugations of the shank, an annular bearing embracing the assembled hemi-cylindrical sleeve sections in fitted relation thereto, and securing said sections in assembled relation in embracing and coaxial relation with the hub, means supporting the assembled retaining sleeve sections in fixed axial position in the barrel and for rotation about their common axis, means securing the blade and retaining sleeve sections for rotation together about said common axis, one of said hemi-cylindrical sleeve sections having an integral extension at its inner end offset therefrom into coaxial rela-

tion to the shank and projecting into the hub, a gear rigid and coaxial with the extension, and driving means in the hub drivingly connected to said gear for varying the pitch of said blade.

6. In a variable pitch propeller, a hub, a blade supporting barrel extending radially of the hub, a blade, a blade shank thereon and having external annular corrugations, a pair of complementary hemi-cylindrical shank retaining sleeve sections embracing the shank and having internal corrugations fitting the corrugations of the shank, an annular bearing race embracing the assembled hemi-cylindrical sleeve sections in close fitted relation thereto and securing said sections in assembled relation in embracing and coaxial relation to the shank, a complementary annular bearing surface in the barrel, bearings interposed between said race and surface for mounting the assembled sections and shank for rotation in the blade supporting barrel, means supporting the assembled retaining sleeve sections in fixed axial position in the barrel, means securing the blade and retaining sleeve sections for rotation together about said common axis, one of said hemi-cylindrical sleeve sections having an integral extension at its inner end offset therefrom into coaxial relation to the shank and projecting into the hub, a gear rigid and coaxial with the extension, and driving means in the hub drivingly connected to said gear for varying the pitch of said blade.

7. In a variable pitch propeller, a hub, a blade supporting barrel extending radially of the hub, a propeller blade, a blade shank thereon and having external annular corrugations, a pair of complementary hemi-cylindrical shank retaining sleeve sections embracing the shank and having internal corrugations fitting the corrugations of the shank, annular bearing races spaced longitudinally of the sections and securing the hemi-cylindrical sleeve sections snug in embracing relation about and in coaxial relation with the shank, the assembled retaining sleeve sections and races being slidable axially in the barrel, radial thrust bearings operatively interposed between the innermost one of the races and the barrel, axial thrust bearings for the outermost one of the races, a thrust bearing race secured to the barrel and adjustable axially thereof and cooperable with the said outermost race of the sections for supporting the retaining sleeve sections for rotation in the barrel and for securing the blade and retaining sleeve sections in fixed axial position in the barrel, means securing the blade and sections for rotation together about said common axis, one of said hemi-cylindrical sleeve sections having inwardly offset an extension at its inner end coaxial with the shank and projecting into the hub, blade driving means carried by the extension, and complementary driving means in the hub drivingly connected to said blade driving means for varying the pitch of said blade.

8. In a variable pitch propeller, a hub, a blade supporting barrel extending radially of the hub, a blade, a blade shank thereon and having external annular corrugations, a pair of complementary hemi-cylindrical shank retaining sleeve sections embracing the shank and having internal corrugations fitting the corrugations of the shank, axially spaced endless metal collars securing the hemi-cylindrical sleeve sections in snug assembled relation about the shank, cooperating bearing means embracing the collars and supported by the hub in coaxial relation there-

with, an annular radial flange on the assembled sections between the collars, spaced retainers for the bearing means in the barrel, one adjustable axially thereof to fix the position of the sleeves and blade shank for rotation in the barrel, one of said hemi-cylindrical sleeve sections having an integral offset extension at its inner end coaxial with the shank and projecting into the hub, and blade driving means rigid with the extension adapted to cooperate with complementary driving means in the hub for varying the pitch of said blade.

9. In a variable pitch propeller, a hub structure having a tubular blade-supporting barrel, a circular blade shank having an annular neck and adjacent annular rib, a mounting shell formed complementary to the neck and rib and comprising complementary relatively large diameter hemi-cylindrical parts, metal bearing collars closely embracing said parts to hold them snugly on the shank, cooperating bearing means in the barrel engaging the collars, one of the hemi-cylindrical shell parts having a reduced diameter inwardly offset, non-split tubular portion integral therewith and connected thereto for half

25

a circumference and forming in effect a rigid pilot projection for and concentric with the inner end of the shell, the inner end of said portion being adapted and arranged for radial thrust engagement with a pilot bearing in the hub structure, said tubular extension having means thereon in the plane of its pilot bearing portion for engagement with a pitch-varying means within the hub structure.
